COMBINED SIDE DART AND STERN HANDLE

Edward W. Peterson, 445 N. Michigan Ave., Chicago, Ill.

Filed Jan. 4, 1960, Ser. No. 58,913

Term of patent 7 years

(Cl. D71—1)

Fig. 1 is a small scale perspective view of a combined side dart and stern handle showing my new design, the boat shown in broken lines being for illustrative purposes only.

Fig. 2 is an enlarged perspective view thereof.

Fig. 3 is a similarly enlarged, side elevational view thereof.

Fig. 4 is a further enlarged, fragmentary, side elevational view of the rear portion thereof.

Fig. 5 is a rear elevational view thereof drawn to the same scale as Fig. 4.

Fig. 6 is a top, plan view of the portion thereof shown in Fig. 4.

Portions of the design are shown broken away in Figs. 4 and 6 for convenience of illustration.

I claim:

The ornamental design for a combined side dart and stern handle, as shown and described.
